ENGINE VALVE.

1,414,152.

Specification of Letters Patent. Patented Apr. 25, 1922.

Application filed December 18, 1917. Serial No. 207,703.

To all whom it may concern:

Be it known that I, CHARLES J. PILLIOD, a citizen of the United States, and a resident of Toledo, in the county of Lucas and State of Ohio, have invented a certain new and useful Engine Valve; and I do hereby declare the following to be a full, clear, and exact description of the invention, such as will enable others skilled in the art to which it appertains to make and use the same, reference being had to the accompanying drawings, and to the characters of reference marked thereon, which form a part of this specification:

This invention relates to valves for controlling the admission and exhaust of an operating fluid to and from the cylinders of fluid-operated engines, other than those of the internal combustion type, and is intended for use more particularly in connection with steam-engines.

The valves and valve-gears heretofore used in connection with steam-engines are confined to two classes, namely, those having a fixed valve travel and those having a variable valve travel, and the present invention relates more particularly to the latter type but is not restricted to use in connection therewith. With valves of the variable travel type heretofore used a change in the variable movement not only effects an adjustment or change in the cut-off but in all other functions of the valve as well, or, in other words, a shortening of the cut-off causes a correspondingly earlier opening and closing of both the admission and exhaust ports, and vice versa. Furthermore, with the valves heretofore used the back-pressure increases with the closing of the cut-off.

The primary object of my invention is the provision of a valve of the character described, in which, if of the variable travel type, the opening and closing of the admission and exhaust ports remain constant for varying positions of the cut-off, whereby objections incident to the use of valves heretofore employed are overcome and a maximum utilization of the heat units obtained, and in which the element of pre-admission remains constant irrespective of any variation in the cut-off, which feature is important, for, with an increase of pre-admission the negative work increases.

A further object of my invention is the

provision of a valve construction of the character described, wherein the different valve members are perfectly balanced during use. Further objects and advantages of the invention will be apparent from the following detailed description thereof.

While the invention, in its broader aspect, is capable of embodiment in numerous forms and of use in numerous connections, an embodiment thereof in connection with a reversible engine and with a gear of the Walschaert type is illustrated in the accompanying drawings, in which—

Figure 1 is a fragmentary side elevation of a locomotive embodying the invention and equipped with a reversing valve-gear of the Walschaert type. Fig. 2 is an enlarged side elevation of a portion thereof, with the valve in central vertical longitudinal section. Fig. 3 is a central horizontal longitudinal section through the valve. Figs. 4, 5, 6 and 7 are cross-sections on the lines 4—4, 5—5, 6—6 and 7—7, respectively, in Fig. 3. Fig. 8 is an enlarged perspective view of the valve-core, with parts broken away. Fig. 9 is a perspective view of one of the stationary end members of the core. Figs. 10 and 12 are perspective views of the outer and inner admission and exhaust valve sleeves, respectively. Fig. 11 is a perspective view of the two cut-off valve-sleeves in operative relation together with their operating means, parts being broken away, and Figs. 13, 14, 15 and 16 are sectional views of the valve in different successive quarter positions of a cycle.

Referring to the drawings, 1 designates a valve casing, which forms a cylindrical valve-chamber having an inlet port 2 at its central portion, a port 3 adjacent to each end in communication with the respective end of the associated engine cylinder 4, and an exhaust port 5 (Fig. 3) adjacent to each end and leading to any suitable point of exhaust. The valve-casing is provided internally with a broadened annular recess 2^a in communication with the inlet port 2, and adjacent to each end with relatively narrow annular recesses 6 and 7, from which the ports 3 and 5 respectively lead. The ends of the valve-casing are closed, in the present instance, by removable heads 8 and 9, from the latter of which rearwardly project bracket-arms 10 and 11 for the purpose hereinafter described.

A core-member 12 of cylindrical form fits into the valve-casing 1, and in its present embodiment has a cylindrical body portion 13, which fits the bore of the valve-casing 5 and is of sufficient length to span the steam distributing recess 2^a and extend slightly beyond the ends thereof. A plurality of ports 14 are provided in annular series radially through the central portion of the 10 core body 13 to open communication between the steam distributing recess 2^a and the interior of the core. The body 13 is provided with internal annular flanges or shoulders 15 in spaced relation to each end 15 and at the outer ends of the ports 14, and a hollow cylindrical extension 16 projects outward from the inner edge of each of these flanges in spaced concentric relation to the respective end of the body, as best 20 shown in Fig. 8. The extensions 16 project beyond the outer ends of the body 13, and each has its ends open with the inner end in communication with the inlet ports 14 and its outer end in communication with the respective end of the valve chamber and the 25 exhaust port 4 leading therefrom. Each extension 16 has two longitudinally spaced annular series of radial ports 17 and 18 and is provided between said series of ports with 30 an interior partition 19, which closes the communication between the opposite end portions of the extension.

A bushing 20 is fitted into each end of the valve-casing 1 in radially spaced relation to 35 the respective core extension 16 and has its inner end provided with a reduced portion 21 for fitting into the adjacent end of the core body 13. The outer end of each bushing 20 terminates adjacent to the outer end 40 of the extension 16, which it surrounds, and to the inner wall of the respective exhaust recess 7. The body portion of each bushing is provided with an annular series of radial ports 22, which open at their outer ends into 45 the adjacent recess 6 in the valve-casing and have their inner ends substantially in radial register with both series of ports 17 and 18 in the respective core extension 16, said ports 22 being sufficiently broadened at their inner 50 ends longitudinally of the bushing to substantially span both sets of said extension ports, as shown in Figs. 2 and 5.

Two telescoped valve-sleeves 23 and 24 are mounted between the extension 16 and 55 the bushing 20, at each end of the core, with the inner sleeve 23 fitted for longitudinal sliding movements on the extension 16 and the outer sleeve 24 fitted within the bushing for longitudinal sliding movements therein 60 and on the sleeve 23. Each set of these valve sleeves have inner sets of radial ports 25 and 26 arranged in annular series and adapted to register with each other and to open communication between the ports 17 and 22 in 65 the core extension 16 and bushing 20 during

a predetermined portion of the relative movements of said sleeves, and have similar sets of ports 27 and 28, respectively, adapted to register with each other and open communication between the ports 18 and 22 of 70 the core extension and bushing, respectively, during a predetermined portion of the relative movement of the sleeves. The longitudinal spacing of the port sets in the two sleeves differs somewhat, the spacing of the 75 port sets in the sleeve 24, in the present instance, being less than the port spacing in the sleeve 23, as best shown in Fig. 2.

Each bushing 20 has its bore enlarged towards its inner end from adjacent to the outer side walls of the ports 22 therein, and a cut-off sleeve 29 has a sliding fit in this enlarged portion of the bushing-bore and on the inner end portion of the associated valve-sleeve 24. The cut-off sleeve, in the present 80 instance, has circumferentially spaced fingers 30 projecting longitudinally from its outer end and tied together, or circumferentially braced relative to the sleeve, by narrow strips 31. The spaces between the fingers 30 register with the ports 22 in the bushing and with the ports 26 and 28 in the valve-sleeve 24. The purpose of the sleeves 29 is to cooperate with the inner set of ports 26 in the respective valve-sleeves 24 to regulate or adjust the period of cut-off of the live steam from the interior of the core to the engine cylinder, and for this purpose the outer end of each cut-off sleeve (disregarding the fingers 30) is disposed in lapping 85 relation to the sleeve-ports 28 during a portion of the movement of the valve-sleeve 24. The cut-off sleeve 29 is stationary during a running of the engine except during an adjustment thereof to vary the cut-off, which adjustment may be accomplished at any time, as is apparent. It is therefore evident that so far as the cut-off feature of the sleeve 29 is concerned, the fingers 30 may be omitted. 90

For the purpose of adjustment, each cut-off sleeve 29 has a rod 32 projecting longitudinally thereof from a lug 33 at its inner end, through a stuffing-box in the head 9, and connected at its outer end by a link 34 to one of a pair of eccentric pins 35 carried by a rock-shaft 36, which shaft is journaled in the bracket-arm 11. A rocker-arm 37 projects from the shaft 36 and may be connected by a rod 38 to any suitable control, as well understood in the art. It is thus evident that a rocking of the shaft 36 in either direction will impart corresponding opposed reciprocatory movements to the cut-off sleeves 29, 29 of the valve. The rods 32 project 100 through a recess or cavity 39 provided longitudinally in the body portion 13 of the valve-core. 105

Each valve-sleeve 23 is provided at its outer end with a yoke 40, and these yokes are 110

rigidly connected by a rod 41, and each valve-sleeve 24 is provided at its outer end with a yoke 42, and these yokes are rigidly connected by a rod 43.

5 It is thus evident that longitudinal movements of the rods 41 and 43 will communicate like movements in unison to the valve-sleeves which they respectively connect. The rods 41 and 43 project at their outer 10 ends through stuffing-boxes in the cylinder head 9 and are respectively connected to cross-heads 44 and 45, which are mounted for movements longitudinally of the valve-casing in guides 46 provided at the outer 15 end of the bracket-arm 10.

The valve embodying my invention is illustrated, in the present instance, in connection with a Walschaert valve-gear of the reversing type, in which 47 is the eccentric rod; 48 the oscillating link fulcrumed to the frame, as at 49; 50 the radius-rod having its forward end pivotally connected to the cross-head 44 and its rear end in shiftable connection with the oscillating 25 link slot; 51 the reversing shaft, which has an arm 52 in connection with a control means and an arm 53 connected to the rear end of the radius-rod through a link 54; 55 the combination lever, which is pivoted adjacent to its upper end to the cross-head 45 and has its upper end fulcrumed to an anchor-link 56 attached to the locomotive frame and its lower end connected by the union-link 57 to the piston-rod cross-head 58.

35 It will be noted that the manner of coupling up this type of gear with my valve differs from the manner of coupling the same to an ordinary valve in that the radius-rod 50, instead of being connected to 40 the combination lever 55, has connection with the set of valve-sleeves 23, 23 while the combination lever has connection with the set of valve-sleeves 24, 24 so that one set of such sleeves is operated by the drive- 45 wheel eccentric and the other set by the piston-rod cross-head. An adjustment of the valve-sleeves 23, 23 for reversing conditions is effected by a shifting of the radius-rod 50 with respect to the oscillating 50 link 48.

It will be understood that while I have particularly shown and described my valve for use in connection with the Walschaert gear, it is not restricted to use in connection therewith, but may be coupled up to any valve-gear of either the radial or eccentric driven type, and may also be used in connection with stationary and marine engines to control the admission of steam 55 to, and its exhaust from, the engine cylinder.

The design of my valve is such that it can be inserted into the valve-casings of engines now in use and substituted for the 60 steam control-valves used therein without

changing the arrangement or location of the ports and the steam distributing channels or recesses in such casings.

In describing the operation of my valve mechanism, reference is made particularly 70 to Figs. 13 to 16, in each of which the points on the circle at the left indicate the relative valve gear positions for the different valve-sleeves, as in all types of gears or operating means for the valve-sleeves the 75 position of the eccentric is 90° in advance of the cross-head movement. For this reason such movements are illustrated diagrammatically at the left of each of said figures and designate the different eccentric and cross-head positions for different 80 positions of the valve-sleeves. In other words, when the cross-head is at the extreme of its movement in either direction the eccentric is at the center of its travel, 85 and vice versa. In Fig. 1, the cross-head is in its center position and the eccentric at its forward extreme position, and these positions correspond to the positions of the parts in Fig. 13. The valve-sleeves in Figs. 90 14, 15 and 16 are each advanced one-quarter revolution over the preceding figure with the engine-wheel or eccentric revolving member running forward.

When the piston in the engine-cylinder is 95 at the center of its travel and moving to the left, for forward running, the valve-sleeves are in the positions indicated in Fig. 13, with the eccentric at the forward limit of its stroke, as indicated by the point *e*, and 100 the cross-head in mid-position of its stroke as indicated at *c*. When the valve-sleeves are in these positions, steam is being admitted to the right end of the cylinder 4 and exhausted from the left end thereof with the 105 respective inlet and exhaust ports substantially half closed by reason of the relative movement of the valve-sleeves 23 and 24 of the two sets. When the drive-wheel has moved one-quarter of a forward turn from 110 such position the piston is approximately at the limit of its back stroke and the valve-sleeves are in such positions that the exhaust ports at the left end of the cylinder are closed and the inlet ports at such end just 115 beginning to open to admit steam back of the piston, while the valve-sleeves at the other end of the valve have moved to partially open the exhaust ports and close the steam ports at the right end of the engine-cylinder, as shown in Fig. 14.

120 As the piston moves to the right the movement of the sleeves causes a gradual increase and then a gradual decrease of the sizes of the inlet ports at the inlet end of the cylinder and of the exhaust ports at the exhaust end thereof, and when the drive wheel has completed a half turn from the position of Fig. 13, the valve-sleeves stand in the positions indicated in Fig. 15. During the third and fourth 125 130

quarter revolutions of the drive-wheel the conditions of admission and exhaust are the same as in the first and second quarters of movement except that they are reversed with respect to the ends of the cylinder, as indicated in Figs. 15 and 16, respectively.

When it is desired to reverse the movement of the engine, as for instance, by shifting the reverse lever 52, 53 in Fig. 1, the 10 action is the same as though the eccentric point *e* in Figs. 13 or 15 was shifted from one horizontal extreme to the other, so that in Fig. 13 the admission and exhaust would be reversed by reason of the valve-sleeves 15 taking the relative positions shown in Fig. 15.

It is evident that to cut off the steam the cut-off sleeves 29, 29 are moved in opposite directions, for instance, by a movement of 20 the control member 38, and that the steam may have a 100% cut-off if desired, although it is usually not practical to exceed a 90% cut-off. The control of the port openings and cut-off sleeves is entirely independent of 25 the exhaust, thereby not sacrificing release to obtain any desired range of steam admission.

It is evident, with the use of my valve, that the opening and closing of the admission and exhaust ports remain constant, while the steam cut-off may be varied at will, thus enabling a maximum efficiency for either the normal running or starting conditions, to be obtained; that the constant 35 events, such as the exhaust release, exhaust closure, steam admission and steam pre-admission, are determined by the design or service requirements, and that the valve sleeves have a perfect balanced action due 40 to an equalizing of the pressure entirely around the same. It is also evident that with my valve there is no limitation as to events to be secured, that is, any release, any closure or any cut-off can be secured.

45 It is found in practice that the provision of the core or plug member which carries the valve-sleeves is quite important for the reason that there is a period in the travel of the valve-sleeves in which the ports 50 thereof must pass each other, and without the inner core or plug these ports would not seal against the pressure but would leave an open passage to the exhaust. The inner core or plug therefore performs two functions, that of assisting in closing the valve ports during portions of the movements of the valve-sleeves, and that of protecting the valve-sleeves from the steam and exhaust pressures during operation.

60 I wish it understood that my invention is not limited to any specific construction, arrangement or form of the parts, as it is capable of numerous changes and modifications without departing from the spirit of 65 the claims, and also that the invention,

which resides particularly in the valve itself, and not in the operating means therefor, may have its different movable members controlled and operated in any suitable manner.

Having thus described my invention, what I claim is new and desire to secure by Letters Patent, is:—

1. In a fluid pressure engine, means forming a valve seat and providing communication at one side of the seat with a source of fluid pressure and at the other side of the seat with an engine cylinder, a set of valves surrounding the seat in cooperating relation thereto and operable to periodically open and close the communication between the source of fluid and cylinder, and a cut-off valve seating on the outer side of one of said first valves relative to the source of fluid and operable to vary the fluid cut-off. 75

2. In a fluid pressure engine, means forming a valve seat and providing communication at one side of the seat with a source of fluid pressure and at the other side of the seat with an engine cylinder, means having a set of relatively movable valves mounted one over the other on said seat and operable to periodically open and close the communication between said source of fluid supply and cylinder, a cut-off valve mounted on the outer of said valves relative to the source of fluid, and means connected with and operable to move said valve to vary the fluid cut-off. 90

3. In a fluid pressure engine, means forming a cylindrical valve seat and providing communication at one side of the seat with a source of fluid pressure and at the other side of the seat with an engine cylinder, a set of valve sleeves mounted one over the other on said seat and operable to periodically open and close the communication between the source of fluid and cylinder, and a cut-off valve sleeve mounted on the other side of one of said first valves relative to the source of fluid and operable to vary the fluid cut-off. 100

4. In a fluid pressure engine, means forming a cylindrical valve seat and providing communication at one side of the seat with a source of fluid pressure and at the other side of the seat with an engine cylinder, means having a set of relatively movable valve sleeves mounted one over the other on said seat and operable to periodically open and close the communication between said source of fluid supply and cylinder, a cut-off valve sleeve mounted on the outer of said valves relative to the source of fluid pressure, and means connected with and operable to move said cut-off valve to vary the fluid cut-off. 115

5. In a fluid pressure engine, a set of sleeve valves, means forming a seat for and enclosing said valves inside and out and pro- 120

viding an exhaust passage and communication at the inner side thereof with a source of fluid pressure and at the outer side with a cylinder of the engine, and means for operating said set of valves to periodically open and close the communication between the source of fluid pressure and cylinder and between the exhaust passage and cylinder.

6. In a fluid pressure engine, a set of sleeve valves, means forming a seat for and enclosing said valves inside and out and providing an exhaust passage and communication at the inner side thereof with a source of fluid pressure and at the outer side with a cylinder of the engine, means for operating said set of valves to periodically open and close the communication between the source of fluid pressure and cylinder and between the exhaust passage and cylinder, and a variable 20 cut-off valve enclosed within said means with said set of valves and cooperating therewith to vary the fluid cutoff.

7. In a fluid pressure engine, a set of sleeve valves, means forming a seat for and enclosing said valves inside and out and providing an exhaust passage and communication at the inner side thereof with a source of fluid pressure and at the outer side with a cylinder of the engine, means for operating said set of valves to periodically open and close the communication between the source of fluid pressure and cylinder and between the exhaust passage and cylinder, and a variable 30 cut-off valve mounted on said valve set at the outer side thereof relative to the source of fluid pressure and periodically protected completely from live fluid pressure by said first means and valve, and means for operating said cut-off valve to vary the fluid cutting off.

8. In a fluid pressure engine two sets of sleeve valves, means forming a valve seat for each valve set and forming a guide for the valves inside and out and also providing fluid supply and exhaust passages at the inner side of each valve set and providing communication at the outer side of each valve set with a cylinder of the engine, and means for operating the valves of each set 45 to periodically open and close the communication between the cylinder and said passages.

9. In a fluid pressure engine two sets of sleeve valves, means forming inner and outer valve seats for each valve set and also providing fluid supply and exhaust passages at the inner side of each valve set and providing communication at the outer side of each valve set with a cylinder of the engine, means for operating the valves of each set to periodically open and close the communication between the cylinder and said passages, and means having a cut-off valve mounted on the outer side of each 50

valve set relative to the respective seat and 65 operable to vary the fluid cut-off.

10. In a fluid pressure engine two sets of sleeve valves, means forming inner and outer valve seats for each valve set and also providing fluid supply and exhaust passages at 70 the inner side of each valve set and providing communication at the outer side of each valve set with a cylinder of the engine, means for operating the valves of each set to periodically open and close the communication between the cylinder and said 75 passages, and means having a cut-off valve mounted on the outer side of each valve set relative to the respective seat and operable to vary the fluid cut-off, the cut-off valves 80 of said last means being completely protected from live fluid pressure by said first means and cooperating valves when the communication between the cylinder and source of fluid pressure is closed. 85

11. In a fluid pressure engine, a set of valve sleeves, means enclosing said sleeves inside and out and forming a valve seat therefor, said means providing fluid supply and exhaust passages at the seat side of the 90 valve sleeves and providing communication at the other side of the said sleeves with a cylinder of the engine, means for operating said set of valve sleeves to periodically open and close the communication between said 95 passages and the cylinder, and a variable cut-off valve sleeve mounted on said valve set at the outer side thereof relative to the source of fluid supply and periodically protected completely from live fluid pressure 100 by said first means and valves, and means for operating said cut-off valve to vary the fluid cut-off. 100

12. In a fluid pressure engine, two sets of sleeve valves, means enclosing said valves and forming a cylindrical valve seat for each set, said means providing fluid supply and exhaust passages at the seat side of each valve set and a cylinder communicating passage at the other side of each valve set, means for operating the valves of each set to periodically open and close the communication between the cylinder passage and said exhaust and supply passages, and means having a cut-off valve sleeved on the outer 110 side of each valve set relative to the respective seat and operable to vary the fluid cut-off. 115

13. In a fluid pressure engine, two sets of sleeve valves, means enclosing said valves and forming a cylindrical valve seat for each set, said means providing fluid supply and exhaust passages at the seat side of each valve set and a cylinder communicating passage at the other side of each valve 120 set, means for operating the valves of each set to periodically open and close the communication between the cylinder passage 125

and said exhaust and supply passages, means having a cut-off valve sleeved on the outer side of each valve set relative to the respective seat and operable to vary the fluid 5 cut-off, and manually controlled means for operating the cut-off valve.

14. In a fluid pressure engine, two sets of sleeve valves, means enclosing said valves and forming a cylindrical valve seat for 10 each set, said means providing fluid supply and exhaust passages at the seat side of each valve set and a cylinder communicating passage at the other side of each valve set, means for operating the valves of each set 15 to periodically open and close the communication between the cylinder passage and said exhaust and supply passages, means having a cut-off valve sleeved on the outer side of each valve set relative to the respective seat 20 and operable to vary the fluid cut-off, said cut-off valves being completely protected from live fluid pressure by said first means and the cooperating valves when the communication between the cylinder passage 25 and the supply passage is closed.

15. The combination with a cylinder of a fluid pressure engine, of a pair of valve sleeves mounted one on the other for relative reciprocatory movements, stationary 30 means forming a guide for said sleeves and having a passage surrounding said sleeves and in communication with an end of said cylinder and having separated fluid supply and exhaust passages interiorly of the valve 35 sleeves, said sleeves each having a series of inlet ports and a series of exhaust ports which successively and respectively register at predetermined periods and open communication first between said cylinder passage 40 and first one and then the other of said supply and exhaust passages, and means for operating said sleeves.

16. The combination with a cylinder of a fluid pressure engine, of a pair of valve 45 members fitted one against the other for relative reciprocatory movements, stationary guide means for said members having a cylinder communicating passage exterior to said members and having separated supply and exhaust passages interiorly of the 50 valve members, said members having ports which periodically register and open communication between said exterior passage and first one and then the other of said interior passages, and means for imparting predetermined relative movements to said members.

17. A valve for fluid pressure engines, having a pair of telescoped valve sleeves 60 mounted for relative reciprocatory movements, a stationary guide means for said sleeves having a cylinder communicating passage exterior to and surrounding said sleeves and exposed at one side thereto and 65 having separate supply and exhaust pas-

sages interiorly of the valve sleeves, said sleeves having annular series of ports which periodically register and open communication between said exterior passage and first one and then the other of said interior passages, and means for imparting predetermined relative movements to said sleeves. 70

18. A valve for fluid pressure engines having a pair of telescoped valve sleeves mounted for relative reciprocatory movements, a stationary guide member having an annular recess in which said sleeves are fitted and adapted to reciprocate, said member having a cylinder communicating passage exterior to and surrounding said sleeves 75 and exposed at one side thereto and having separate supply and exhaust passages interiorly of the valve sleeves, said sleeves each having a series of ports for each interior passage and adapted to respectively 80 register to open communication between said exterior passage and first one and then the other of said interior passages, and means for imparting predetermined relative movements to said sleeves. 90

19. The combination with a cylinder for a fluid pressure engine, of stationary means forming exterior passages adjacent to each end of the cylinder in communication therewith and forming separate interior supply 95 and exhaust passages for each exterior passage, a set of telescoped sleeve valves carried by said means for relative movements between each of said exterior passages and the associated supply and exhaust passages 100 and adapted to close the communication therebetween, said interior passages being disposed interiorly of the valve sleeve, and said valves having ports which periodically register to open communication between an exterior passage and first one and then the other of the associated supply and exhaust 105 passages, and means for imparting predetermined relative reciprocatory movements to said valves. 110

20. The combination with a cylinder of a fluid pressure engine, of stationary means having a hollow interior divided into two chambers, with one in communication with live steam and the other forming part of an exhaust passage and both having communication with one end of the cylinder, sleeve valves guided inside and out by said means and adapted to close the communication between said chambers and the cylinder and having ports adapted to periodically register during relative movements of the valves to open communication between the cylinder and first one and then the other of said chambers, and means for imparting relative movements to said valves. 115

21. In a valve mechanism, means forming two spaced sets of inlet and exhaust passages, a set of control valves for each set of said passages and comprising a plural- 120 125 130

- ity of relatively movable valve sleeves adapted when relatively moved to periodically open and close each of the associated passages, means for imparting predetermined constant relative movements to the sleeves of each valve set, and an adjustable sleeve mounted on a valve sleeve of each set and operable to regulate the period of cut-off of each inlet passage.
- 10 22. A valve mechanism, as called for in claim 21, in which the cut-off sleeve is disposed at the outer sides of the valve sleeves of each set relative to the source of fluid supply.
- 15 23. In a valve mechanism, means having a hollow cylindrical portion at each end, a partition in each portion dividing it into axially spaced inlet and outlet chambers with radiating ports in each chamber, said means also forming a cylinder communicating passage in spaced surrounding relation to each cylindrical portion thereof, a set of telescoped valve sleeves mounted in each of said cylindrical portions for relative reciprocatory movements and having sets of ports which periodically register with each other and with said radiating ports to open communication between an associated cylinder passage and first one and then the other of the adjacent inlet and outlet chambers, and means for imparting predetermined reciprocatory movements to said valves.
- 20 24. In a valve mechanism, means having a hollow cylindrical portion at each end with each cylindrical portion forming axially spaced inlet and outlet chambers having radiating ports, said means also forming a cylinder communicating passage in spaced surrounding relation to each cylindrical portion thereof, a set of telescoped valve sleeves mounted in each of said cylindrical portions for relative reciprocatory movements and having sets of ports which periodically register with each other and with said radiating ports to open communication between an associated cylinder passage and first one and then the other of the adjacent inlet and outlet chambers, and means for imparting predetermined reciprocatory movements to said valves.
- 25 25. The combination with a valve-casing having a cylinder communicating passage and an exhaust passage at each end, of a valve mechanism mounted in said valve-casing and embodying a core forming a fluid inlet passage in communication with each cylinder passage of the casing, and an exhaust passage between the cylinder and exhaust passage at each end of the casing, a valve set mounted in each end portion of the core for relative reciprocatory movements longitudinally thereof and operable to periodically open communication between the cylinder passage and first one and then the other of said core inlet and exhaust passages at the adjacent end of the cylinder, means for imparting predetermined relative reciprocatory movements to the valve members of each set, a cut-off valve of cylindrical form sleeved on each set of said valves, and means connected to said cut-off valve and adjustable independently of the valve sets to vary the fluid cut-off from the core inlet passage to the associated cylinder passage.
- 30 26. The combination with a valve-casing having a cylinder communicating passage and an exhaust passage at each end, of a valve mechanism mounted in said valve-casing and embodying a core forming a fluid inlet passage in communication with each cylinder passage of the casing, and an exhaust passage between the cylinder and exhaust passage at each end of the casing, a valve set mounted in each end portion of the core for relative reciprocatory movements longitudinally thereof and operable to periodically open communication between the cylinder passage and first one and then the other of said core inlet and exhaust passages at the adjacent end of the cylinder, means for imparting predetermined relative reciprocatory movements to the valve members of each set, a cut-off valve of cylindrical form sleeved on each set of said valves, and means connected to said cut-off valve and adjustable independently of the valve sets to vary the fluid cut-off from the core inlet passage to the associated cylinder passage.
- 35 27. In a valve mechanism, means forming inlet and outlet passages, a set of three valves of cylindrical form sleeved one on another and mounted for relative longitudinal reciprocatory movements in a part of said means, two of said valve members being operable to periodically open and close each of said passages and the other valve member being operable to vary the period of opening of the inlet passage by said first two valve members and being the most remote from the source of fluid supply, means for imparting constant relative reciprocatory movements to said first two valve members, and means connected to said third valve member and operable to impart predetermined variable movements thereto.
- 40 28. In a fluid pressure engine, means forming fluid pressure supply and exhaust passages, a cylinder passage and a valve receiving recess, said recess having ports in opposing walls in communication with said passages and being closed to the supply passage except through said ports, a fluid control valve mounted in said recess and operable to periodically open and close the communication between the cylinder passage and the supply and exhaust passages, and means for operating said valve.
- 45 50 55 60 65 70 75 80 85 90 95 100 105 110 115 120 125 130

29. In a fluid pressure engine, means forming fluid pressure supply and exhaust passages, two cylinder passages and a valve receiving recess for each cylinder passage, 5 said recesses each having ports in opposing walls in communication with the respective cylinder supply and exhaust passages and being closed to the supply passage except through said ports, a fluid control valve set 10 mounted in each of said recesses and operable to periodically open and close the communication between the respective cylinder passage and the associated supply and exhaust passages, and means for operating said 15 valves.

30. In a fluid pressure engine, means forming fluid pressure supply and exhaust passages, a cylinder passage and a valve receiving recess, said recess having wall ports 20 in communication with said passages and being closed to the supply passage except through said ports, a fluid control valve mounted in said recess and operable to periodically open and close the communication 25 between the cylinder passage and the supply and exhaust passages, means for operating said valve, and a cut-off valve mounted in the recess with said first valve and operable to cooperate with said valve to vary the fluid 30 cut-off.

31. In a fluid pressure engine, means forming fluid pressure supply and exhaust passages, two cylinder passages and a valve receiving recess for each cylinder passage, 35 said recesses each having ports in communication with the respective cylinder supply and exhaust passages and being closed to the supply passage except through said ports, a fluid control valve set mounted in each of 40 said recesses and operable to periodically open and close the communication between the respective cylinder passage and the associated supply and exhaust passages, means for operating said valves, and a fluid cut-off 45 valve mounted in each of said recesses and operable to cooperate with the respective valve set to vary the fluid cut-off.

32. In a fluid pressure engine, two sets of 50 valves, means forming a valve seat for each valve set and enclosing said valves to protect the ends of the valves adjacent to the live fluid pressure from such pressure, said means also providing fluid supply and exhaust passages at the inner side of each valve set and providing communication at the 55 outer side of each valve set with a cylinder of the engine, and means for operating the valves of each set to periodically open and close the communication between the cylinder and the respective supply and exhaust 60 passages.

33. In a fluid pressure engine, a set of 65 telescoped valve sleeves, means forming a valve seat for said valves and enclosing the sleeves to protect the ends thereof adjacent

to the live fluid pressure from such pressure, said means providing fluid supply and exhaust passages at one side of said valves, and providing communication at the other side of the sleeves with the cylinder of the engine, and means for operating said valves to periodically open and close the communication between said passages and cylinder. 70

34. In a fluid pressure engine, two sets of 75 valve sleeves, means forming a valve seat for each sleeve set and enclosing the sleeves to protect the ends thereof adjacent to the live fluid pressure from such pressure, said means also providing fluid supply and exhaust passages at one side of each sleeve set, and providing communication at the other side of each set with a cylinder of the engine, and means for operating the valves of each set to periodically open and close the communication between the cylinder and the respective supply and exhaust 80 passages.

35. In a fluid pressure engine, two sets of 85 valves, means forming a seat for each valve set and enclosing the valves to protect the end portions thereof adjacent to the live fluid pressure from such pressure, said means also providing fluid supply and exhaust 90 passages at one side of each valve set and providing communication at the other side of each valve set with the cylinder of the engine, and means for operating the valves of each set to periodically open and close the communication between the cylinder and the respective supply and exhaust 95 passages.

36. In a fluid pressure engine, two sets of 100 valves, means forming a seat for each valve set and enclosing the valves to protect the end portions thereof adjacent to the live fluid pressure from such pressure, said means also providing fluid supply and exhaust 105 passages at one side of each valve set and providing communication at the other side of each valve set with the cylinder of the engine, and means for operating the valves of each set to periodically open and close the communication between the cylinder and the respective supply and exhaust 110 passages, and a variable cut-off valve enclosed in said first means in cooperating cut-off relation to each valve set. 115

37. In a fluid pressure engine, a set of 120 valve sleeves, means forming a valve seat for enclosing said valves to protect the ends thereof adjacent to the live fluid pressure from such pressure, said means providing fluid supply and exhaust 125 passages at one side of said valves and a cylinder communicating passage at the other side of the valves, and means for operating the valves to periodically open and close the communication between the cylinder and said passages.

38. In a fluid pressure engine, a set of 130 main and cut-off valves mounted in cooperating relation one on the other, means form-

ing a valve seat for one of said valves and enclosing all of the valves to protect the end portions thereof adjacent to the live fluid pressure from such pressure, and also providing fluid supply and exhaust passages at one side of said valves and a cylinder communicating passage at the other side of the valves, and separate means for imparting predetermined relative operating movements to said valves.

39. In a fluid pressure engine, two sets of main and cut-off valve sleeves in cooperating relation one over another, means forming a valve seat for one of the valves of each set and enclosing all of the valves to protect the ends thereof adjacent to the live fluid pressure from such pressure, said means also providing fluid supply and exhaust passages at one side of each valve set and a cylinder

communicating passage at the other side of each set, and separate means for operating the main and cut-off valves of said sets to impart predetermined relative operating movements thereto.

40. In a fluid pressure engine, means forming fluid pressure supply and exhaust passages, a set of constant travel valves working one over another for controlling the admission and exhaust of fluid to and from an engine cylinder, a variable travel cut-off valve cooperating with one of the constant travel valves to cut off the fluid supply to the cylinder at any predetermined point of travel of the cooperating valve.

In testimony whereof I have hereunto signed my name to this specification.

CHARLES J. PILLIOD.
